Primary Examiner — Abraham Bahta(74) *Attorney, Agent, or Firm* — Schneider IP Law LLC; Laura A. Schneider(57) **CLAIM**

The ornamental design for a child-resistant packaging, as shown and described.

DESCRIPTION

FIG. 1 is a front side view of a child-resistant packaging; FIG. 2 is a rear side view of the child-resistant packaging-in FIG. 1;

FIG. 3 is a front side view of the child-resistant packaging-in FIG. 1 in a partially torn state; and,

FIG. 4 is a top view of the child-resistant packaging-in FIG. 3, shown with the top portion completely torn off, illustrating the press-on closure mechanism on the interior of the bag.

The uppermost broken line in each of FIGS. 1-3 is used to indicate a perforation line and forms part of the invention. The remaining broken lines are for illustrative purposes and form no part of the claimed invention.
